UNITED STATES PATENT OFFICE.

CHARLES L. HINES, OF COUNCIL BLUFFS, IOWA.

WASHBOARD.

1,377,885.

Specification of Letters Patent. Patented May 10, 1921.

Application filed November 25, 1919. Serial No. 340,595.

To all whom it may concern:

Be it known that I, CHARLES L. HINES, a citizen of the United States of America, residing at Council Bluffs, in the county of 5 Pottawattamie and State of Iowa, have invented new and useful Improvements in Washboards, of which the following is a specification.

The object of the invention is to provide 10 a simple and efficient means in connection with a washboard of the ordinary rubbing type, for holding the laundry soap in proper and convenient position to enable the operator to bring the clothes or fabrics which are 15 being rubbed upon the board into contact with the soap merely by a continuation of the rubbing motion and without the necessity of manually applying the soap to the articles as in the ordinary practice, and in 20 this connection to provide means whereby the cake or cakes of soap supported in the holder may be advanced from time to time to arrange the exposed surface thereof within reach in the rubbing operation, to 25 compensate for the wearing away or removal of the surface of the soap in the use thereof, and with these objects in view the invention consists in a construction and combination of parts of which a preferred embodiment is shown in the accompanying 30 drawing, wherein:

Figure 1 is a front view of the device applied in the operative position to a washboard.

Fig. 2 is a sectional view of the same on the plane indicated by the line 2—2 of Fig. 1.

Fig. 3 is a rear view.

Fig. 4 is a front view of the follower.

Fig. 5 is a detail view enlarged of the extremity of the follower feed screw.

The device embodying the invention is applicable to any ordinary commercial form of washboard such as indicated at 10 and which is usually provided above the upper 45 edge of the rubbing surface 11 with a channel or seat 12 for the reception of a cake or cakes of laundry soap, and mounted in this seat in a suitable guide 13 held in place, for example, by fastening screws 14, is a follower 15 with which is connected one extremity of a feed screw 16 threaded in a nut 17 which is seated in the rear wall 18 of the board. The feed screw or stem 16 is preferably connected as by a swivel head 19 with 50 said follower so that by the turning of the screw through a wheel or handhold 20 at

tached to the rear end thereof the follower may be advanced as the cake or cakes of soap in front of the follower become worn, to cause the projection of the front surface 60 or surfaces of said cake or cakes sufficiently beyond the front surface of the frame of the board to be within reach of the fabrics which are being moved upon the rubbing surface in the ordinary operation of the device. The guides 13 are preferably flanged at their upper and lower edges as shown at 65 21 to hold the follower in a fixed path of movement and in practice it has been found convenient to arrange two bars of ordinary 70 laundry soap in the pocket, said bars being arranged in end to end relation, so that practically the entire space between the terminal guides 13 is occupied thereby. The attachment of the wheel or hand-hold 20 to the 75 feed screw is indicated in detail in Fig. 5 wherein said screw is provided with a squared or angular seat 22 for engagement by the hub of said wheel, while a threaded bore 23 therein is adapted for the reception 80 of a retaining screw indicated at 24.

Located above the plane of the follower is a presser foot 25 adapted to bear upon the upper edges of the cakes of soap arranged in the seat in advance of the follower, said presser foot consisting of a plate provided with a stem 26 extending through a guide slot 27 in the rear wall of the frame of the washboard and fitted with a thumb nut 28. The function of the presser foot is 90 to hold the cakes of soap firmly in position, to prevent the displacement thereof by the rubbing contact therewith of the fabrics in the course of washing the same, and the front edge of the presser foot is preferably 95 set back from the front surface 29 of the washboard frame sufficiently to enable the fabrics which are being washed to be rubbed vigorously across the surfaces of the cakes of soap without coming in contact with said 100 presser foot and as above noted, the follower may be adjusted from time to time in the course of the operation to maintain the cakes of soap with their front surfaces projected slightly beyond the plane of the 105 front surface of the frame, as indicated by the dotted lines in Fig. 2.

It will be understood moreover that the soap holding device may be applied to a washboard of the ordinary construction 110 merely by inserting the guides 13 as indicated and providing openings in the rear

wall of the frame of the board for the reception of the feed nut 17 and the plate 30 upon which the stem of the follower is mounted. Also the projection of the feed screw beyond the rear surface of the board does not interfere with the use of the latter in a tub or similar receptacle as in the ordinary practice.

What is claimed is:

10. The combination with a washboard having a soap receiving seat of terminal flanged guides secured to the washboard frame at the extremities of said seat, a follower terminally mounted in said guides for movement toward and from the plane of the rubbing surface of the board, a screw for advancing said follower and having engage-
- 15

ment with a feed nut carried by the washboard frame, and a presser foot for contact with the upper edge of a cake of soap arranged in said seat, the said presser foot consisting of a plate provided with a stem centrally disposed with reference to the length of the plate and lying in substantially the same plane with the latter, the 25 stem projecting through a vertically disposed slot in the washboard frame and receiving on its free extremity a wing nut by means of which it may be adjusted toward or away from said follower.

In testimony whereof I affix my signature.

CHARLES L. HINES.
